LOCKING MECHANISM FOR IRONING MACHINES

Nicholas L. Etten, Waterloo, Iowa, assignor, by mesne assignments, to Chamberlain Corporation, a corporation of Iowa

Application September 21, 1931
Serial No. 564,021

2 Claims. (Cl. 68—9)

This invention relates to improvements in ironing machines of that type having a stationary frame member and a movable arm or frame member pivotally mounted near one end and adapted to support a presser head and to be moved from a closed to an open position.

In this type of ironing machines the free end of the movable frame member is attached to the free end of the fixed frame member by a suitable locking mechanism, thus forming a closed frame when locked with the presser members within the frame, the locking mechanism more or less interfering with the placing of large articles to be ironed between the presser members.

It is, therefore, the object of my invention to provide an improved locking mechanism for the swinging arm adapted to be attached to the pivoted end of the swinging arm to lock the free end of the frame member against outward movement and to leave one end open, and in connection therewith hand actuated means attached to the free end of the pivoted frame for operating the locking mechanism.

My invention consists in the construction, arrangement and combination of the various parts of the device, whereby the objects contemplated are attained, as hereinafter more fully set forth, pointed out in my claims, and illustrated in the accompanying drawing, in which:

Figure 1 is an end elevation of the frame members and the presser supporting arms, showing the manner in which my improved locking mechanism is applied thereto.

Figure 2 is a side elevation of the same.

Figure 3 is a detail view of the rear end of one of the stationary frame members and its co-acting pivoted arm, showing the manner in which the lock is applied thereto.

Referring to the accompanying drawing, I have used the reference numeral 10 to indicate a supporting member, which is adapted to be moved upwardly and downwardly a slight distance by means of suitable fluid operated mechanism 33 such as is in common use.

The upper end of the member 10 has what is commonly known as a buck 11, which is designed to move toward and from the head member 12 a slight distance and to apply pressure to the head member after the article to be ironed has been inserted between them.

The head 12 is supported by a pair of pivotally mounted arms 13, each of said arms comprises a pair of spaced plates 14 secured together by suitable spacers 15. The head 12 is secured to

the outside members 14 by means of suitable brackets 16.

The under surface of each of the members 14 near its rear end is provided with a downwardly extended portion 17 designed to support a pivot 18 carried by upwardly extending portions 19 of the stationary frame members 20. The members 20 have rearwardly extending portions 21 designed to support a pivot 22 on which a bell crank lever 23 is mounted.

The lever 23 is mounted between the members 21 and has a vertical leg 24 and a horizontal leg 25. The upper end of the leg 24 is pivotally connected to a link 26 which in turn is pivotally connected to the rear end of the arm 13 by means of a pivot 27. The arm 26 has an upwardly extended portion 28, to which one end of a link 29 is pivotally connected. Said link 29 projects forwardly and between the members 14 and terminates near the forward end of said members.

Pivotedly mounted between the forward ends of the members 14 is a rock arm 30, the upper end of which is pivotally connected with the link 29. The lower end of the arm 30 is attached to one end of a handle 31. The opposite end of said handle is connected to the arm 30 in the manner clearly illustrated in Figure 1.

The members 24 and 26 form what I shall term toggle links designed to have their inner pivoted ends swing inwardly as the free ends of the arms 13 are elevated, as illustrated by dotted lines in Figure 2, in which case the lower end of the arm 30 is swung outwardly.

It will readily be seen that by this arrangement the handle 31 is supported outwardly from the free ends of the arms 13, in such a manner that the weight of the handle 31 will have a tendency to swing its lower end inwardly and its upper end outwardly to assist in returning the toggle links from their dotted line position to the solid line position, and to cause the pivot centers of said links to move outwardly past dead center. This outward movement is limited, however, by the horizontal leg 25 engaging a stop 100 pin 32.

By this arrangement it will further be seen that if upward pressure is applied to the under side of the free end of the arms 14, the rear ends of said arms will be moved downwardly, placing the links 24 and 26 under compression strain, tending to buck their pivot centers outwardly. Said outward movement is limited, however, by the pin 32, thus locking the free ends of the arms 14 against outward movement.

To release the lock, the operator simply grasps the handle 31 and moves it outwardly a slight distance, after which the free ends of the arms 14 may be swung upwardly.

5 In actual operation the member 10 is normally lowered to the dotted line position illustrated in Figure 2, with the arms 14 in their dotted line position. The article to be ironed is then placed on the buck 11. The arms 14 are lowered, carrying 10 with them the head member 12, said arms being locked against upward movement. The buck 10 is then elevated by the fluid operated mechanism 33 and pressure applied in the usual manner.

15 Thus it will be seen that I have provided a locking mechanism for the swinging arms of an ironing machine, which is connected to the rear end of the swinging arm in such a manner as to leave a space between the free ends of the arms 20 and the forward end of the frame members 20, so that large articles being ironed, such as sheets, 25 may have one of their side edges project downwardly and outward through the space between the free ends of the movable arms and the stationary arms.

I claim as my invention:

1. In a device of the class described, a support, a pressing buck mounted on said support, a pair of spaced and parallel arms pivoted to said support, a head mounted on the forward end of said arms over said buck, said arms having rearwardly extending portions, toggle links for pivotally connecting the rearwardly extending portions of said arms to the support, the outer ends 30 of one set of corresponding links each having a leg extending laterally thereto, the outer ends 35 of the other set of corresponding links each having a portion extending longitudinally thereof,

a rock arm pivotally mounted to the free end of each of the first arms, a link pivotally connecting one end of each rock arm with the longitudinally extending portion of a corresponding one of said toggle links, a handle carried by the free ends of said rock arms, and stop pins mounted to engage the laterally extending legs of said links to lock said toggles in straightened position and said head in pressing engagement with said buck, whereby an operator may grasp the handle and by a single outward and upward movement first unlock the toggle and finally to swing the free ends of said arms to an open position.

2. In a device of the class described, a support, a pressing buck mounted on said support, a pair of spaced and parallel arms pivoted to said support, a head mounted on the forward end of said arms over said buck, said arms having rearwardly extending portions, toggle links for pivotally connecting the rearwardly extending portions of said arms to the support, the outer ends of one set of corresponding links each having a portion extending longitudinally thereof, a rock arm pivotally mounted to the free end of each 100 of the first arms, a link pivotally connecting one end of each rock arm with a longitudinally extending portion of a corresponding one of said toggle links, a handle carried by the free ends of said rock arms, means for limiting the movement of said toggle links in one direction to lock said toggles in a straightened position and said head in pressing engagement with said buck, whereby an operator may grasp the handle and by a single outward swinging movement first 110 unlock the toggle and finally swing the free ends of said arms to open position.
